CLAIM

The ornamental design for a bucket base edge shroud system, as shown.

DESCRIPTION

FIG. 1 is a pictorial view of the bucket base edge shroud system showing our new design.

FIG. 2 is another pictorial view of the bucket base edge shroud system.

FIG. 3 is a top view of the bucket base edge shroud system.

FIG. 4 is a bottom view of the bucket base edge shroud system.

FIG. 5 is an enlarged right side view of the bucket base edge shroud system.

FIG. 6 is an enlarged left view of the bucket base edge shroud system.

FIG. 7 is a front view of the bucket base edge shroud system; and,

FIG. 8 is a rear view of the bucket base edge shroud system.

1 Claim, 8 Drawing Sheets
